UNITED STATES PATENT OFFICE

FREDERICK W. LINAKER AND THEODORE M. BRUBACK, OF DU BOIS, PENNSYLVANIA

ROTARY SOOT CLEANER FOR BOILERS

Application filed October 20, 1926. Serial No. 143,027.

This application is in part a continuation of our application No. 631,644, filed April 12, 1923, Patent No. 1,748,387. It also in part presents certain new matter of invention which is not disclosed in said application.

This invention relates to soot cleaners or blowers for water tube boilers of the type having a rotary or oscillatory tubular unit or element into which steam (or other cleaning fluid) is admitted through a suitable valve, and from which it issues in jets from nozzles provided at intervals in the side of such tubular element.

It also relates to such soot blowers wherein the steam is admitted to the rotary element from a stationary head in which the rotary element turns, the valve for controlling the flow being located within such head.

Heretofore in such soot blowers the tubular element or blower unit has been rotated and has been provided with means whereby its rotation opens and closes the valve. According to the present invention the means for applying rotative motion engages the valve, so that its first movement opens the valve, whereupon its continued movement carries the soot blower or element with it throughout a prescribed arc of rotation, the valve being closed upon the application of power to turn it in the contrary direction, whereby the rotary element is turned back to its original position; the valve being closed at either the beginning or end of this return movement, according to the specific mechanism provided.

Two embodiments of the invention are illustrated. In the first, which is shown in Figures 1 to 7 inclusive of the drawings, the valve is turned from its closed position of rest by a movement of the operating means in one direction whereby it first is opened and afterward carries the rotary element with it; and at the beginning of the return movement the valve is first closed and afterward carries the element with it in its rotation back to the initial position.

The second embodiment is shown in Figs. 8 to 15 inclusive (which formed Figs. 12 to 19 of our aforesaid application No. 631,644) to which reference will be made.

Referring to the accompanying drawings,—

Figure 1 is a vertical longitudinal section in a plane parallel with the axis of rotation of the blower element.

Fig. 2 is an end elevation viewed from the left in Fig. 1 and partly broken away.

Figs. 3, 4 and 5 are transverse sections in the planes of the line 3—5 in Fig. 1, showing the valve and blower element in three different positions.

Figs. 6 and 7 are elevations viewed from opposite sides of the valve and valve seat members, which are shown in section in Fig. 1.

The figures taken from our aforesaid prior application are the following:

Fig. 8 is a sectional elevation on the same plane as Fig. 1.

Fig. 9 is a transverse section on the line 9—9 in Fig. 8.

Figs. 10 and 11 are sectional views on the line 10—10, Fig. 8, the locking member or pawl being shown in different working positions.

Fig. 12 is a detached view of the valve seat, the parts being partly in section and partly in plan.

Fig. 13 is a detached view of the valve disk.

Fig. 14 is a view similar to Fig. 9, showing the valve parts in position where the ports are open.

Fig. 15 is a fragmentary view of a boiler showing the cleaning element, and its operating means, applied thereto.

Referring to Figs. 1 to 7, inclusive, 10 is the rotary element or blower unit, which as usual passes freely through a bushing 12 set in the boiler wall or setting 14, with the usual appliances for closing the clearance space around the element. The element, as usual, consists of a portion 10' which projects within the boiler and has the usual steam jet nozzles and is united by a collar or union 11 to the usual elongated nipple 10" which extends into the head 16 (being provided with a stuffing box 20). This head has a chamber 17 receiving steam (or any other cleaning fluid) from a pipe 18. Within the chamber 17 there is fastened on the end of the nipple 10" a

locking member or pawl 19 which is held in position by a lock washer 21. The valve 22 is held in the seat 23 by a lock washer 24.

The valve 22 is provided with a seat 23 which is held in the head 16 by a lock washer 24. The valve 22 is provided with a seat 23 which is held in the head 16 by a lock washer 24.

The valve 22 is provided with a seat 23 which is held in the head 16 by a lock washer 24. The valve 22 is provided with a seat 23 which is held in the head 16 by a lock washer 24.

10" a valve seat member 19 which may conveniently be screwed upon the threaded end of the nipple and held from turning by a key 81; the member 19 has a valve seat 30 which in this instance is arranged eccentrically to the axis of rotation. A valve 21 which may close over the valve seat 30 is carried by a swinging arm 22 which is keyed on the end of a rotary spindle or operating shaft 23. The outer end of the head 16 is closed by a cap 24 suitably fastened to it by cap screws or otherwise, and having a bracket arm 25 which forms an outer bearing for the spindle 23. Keyed on this spindle is a wheel 33 or 15 any other suitable means by which this spindle may be turned. In the particular construction shown, this wheel 33 is a gear wheel which is in mesh with a pinion 34 on a spindle 35 on which is keyed a sprocket wheel 36 carrying a sprocket chain by which it may be turned to rotate the spindle 23 and thereby operate the valve-carrying arm 22.

The arm 22 is of the shape shown best in Figs. 3, 4 and 5, having a hub receiving the 25 spindle 23, an annular socket portion 26 encircling the neck of the valve 21, and a tail portion 27 which turns backward and works between two shoulders 28, 29 formed on the seat member 19. This seat member is broadened at 31 to form a face upon which the valve may slide when turned to the position shown in Fig. 5. The valve is pressed against the seat or the face 31 by a spring 32 which reacts against a cup 37 which in turn reacts 35 against an annular face 38 formed on the inner side of the cap 24, so that in any position of the valve the spring acts to press it against either its seat or the face 31.

It is preferable to attach to the head 16 a 40 casting 39 supporting a ball bearing 40 for the blower element.

In operation, starting from the position shown in Figs. 1 and 4, the spindle 23 is first turned in the direction of the arrow ω ; this 45 swings the valve to the left and opens it, as shown in Fig. 5; during this movement of the arm and valve the element and its seat member remain stationary by reason of the friction generated in the stuffing box 20 and 50 elsewhere. On reaching the position shown in Fig. 5, the tail 27 of the valve arm strikes the shoulder 28 on the valve seat member and thereafter carries the valve seat member with it in its rotation through any desired number 55 of degrees, according to the arc through which in any given position of the element in a boiler it is desired to cause the cleaning jets to sweep against the boiler tubes. Thus, for example, it may turn through an arc of 60 about 50 degrees, this being the movement of the element from the position shown in Fig. 5 to that shown in Fig. 3; or it may turn through any greater arc that is desired, short of a complete rotation. The precise arc 65 through which it turns is determined by the

setting of an adjustable stop 41 on the wheel 33, which may be set around to any circumferential position on this wheel; when this stop strikes a fixed stop 42 (best shown in dotted lines in Fig. 5) the rotation is stopped (this being the position shown in Fig. 3). The operator has then to turn the spindle 23 in the contrary direction in order to rotate the parts back to their original starting point. This, in the construction shown, is accomplished by pulling the opposite side of the sprocket chain. During the first part of this return movement the rotary element (being held frictionally as before) remains motionless, while the valve arm swings the valve back onto the valve seat and thereby closes the opening, so as to shut off steam from the element. The continued rotation, after striking shoulder 29, turns both the valve and element back to the starting point, and when this point is reached, the movement is stopped by a stop projection 43 on the wheel 33, striking the fixed stop 42, as shown in Fig. 2.

Thus the opening and closing of the valve are performed automatically as a necessary incident to the usual turning of the blower element, which is commonly accomplished by a pendant sprocket chain hanging down from the head to a level on the boiler wall where it is readily reached by the operator. 90 The first movement opens the valve, and the continued movement turns the blower element while the steam is blowing through it; it is thus turned through its proper arc of travel, and when stopped at the end of this arc, the operator turns it back to its starting position, the first part of this return movement closing the valve, so that during the remainder of the return movement the steam is shut off from the element. 100

When it is desired to maintain the steam blowing during the return rotation of the element, a somewhat less simple mechanism may be provided, an example of which is shown in Figs. 8 to 15. To accomplish this result it is necessary, after the valve is open, to lock it fast with respect to the valve seat and element, so that the valve cannot close during the return movement until the element has been restored to its initial or starting position, after which by a continued or surplus movement the valve is closed. 110

Figs. 8 to 15 show a more complete form of the invention whereby it is designed to perform the function last stated. These 120 figures also show a different type or construction of valve and seat member, the valve in this instance being a rotary disk valve mounted concentrically with the axis of the blower element and having radial ports which in the open position are coincident with similar ports in the seat member.

Coming now to describe the construction set forth in Figs. 8 to 15, the reference 130

numerals 10, 12, 14, 16, 18 and 20 designate the same parts or parts corresponding in function to those already described with reference to the first embodiment. The valve seat member fixed to the element 10 is here designated 80, and 82 designates the rotary disk valve or valve-proper co-operating therewith. The seat member 80 carries a bracket 84 in which is pivotally mounted a locking pawl or member 86, its pivot being marked 87.

In this construction, the means 33 for turning the element 10 is mounted upon a stem 89, which has a knob and socket connection 90, with the valve part or disk 82, a spring 92 being inserted in said socket for pressing said disk 82 against the valve seat.

The valve part 82 (Fig. 13), which is turned by the element operating means, is provided with a lug 95, which engages a recess 96 in the pawl 86.

The turning of the pawl 86 is controlled by an annular guide 98 projecting from the inner wall of the head 16 and having a recess 99 therein, permitting turning of the pawl 86 in that position of the parts where the valve is to be closed. A projection 101 on the valve part 80 coacts with a stop or shoulder 102 on the head 16 (Fig. 14) to stop the movement of the said valve part 80 in that position where the pawl 86 is opposite the recess 99, and where disengagement of the lug 95 on the valve part 82 takes place and permits closing of the valve.

A stop 104 on the same part 80 which carries the stop 101, coacting with a projection 105 on the valve part 82 stops the movement of the said part 82 in a position where the ports 29 thereof are completely out of registry with the corresponding ports or openings 30' in the valve part 80.

A shoulder 106 on the valve part 80, coacting with the projection 105 on the turned valve part 82, is so placed with relation to the recess 99 that contact between the projection 105 and the shoulder 106 is made at the time the lug 95 is fully engaged in the recess 96 therein, and the said pawl 86 is opposite to said recess 99. Hence, the projection 105, upon coming into contact with the shoulder 106 on the valve part 80, starts the movement of said latter valve part. After the pawl 86 moves past the recess 99, movement thereof is prevented by the means 98, and the lug 95 is held locked by the pawl, so that the two valve parts 80 and 82 move together in either direction under the action of the turning means 33.

In the position of rest between operations, the valve being closed, the parts are as shown in Figs. 8, 9 and 10, the pawl 86 being engaged with the recess 99 and held against turning by the projection 95 engaging its tail 111, as shown in Fig. 10. The valve is thus locked in its closed position.

To open the valve, the operating means 33 is turned in a clockwise direction. The valve part 82 is turned, movement of the valve part 80 being temporarily prevented by the engagement of the pawl 86 in the recess 99. When the lug 95 enters the recess 96 in the pawl 86, however, the latter is free to turn and move out of the recess 99, as shown in Fig. 11, so that the subsequent turning of the valve disk 82 opens the valve. The tail 111 of the pawl 86 in this position engages the part 110, so that the movement of the pawl is limited to the position shown in Fig. 11. At this time the projection 105 strikes the shoulder 106 on the valve part 80, causing this later to move, and the two valve parts 80 and 82 thereafter move in unison with the ports 29 and 30' in registry and the valve fully open. After the pawl 86 passes the position of the recess 99, the means 33 may be turned in either direction without disengaging the lug 95 from the pawl 86, and consequently with the ports 29 and 30' fully open. Thus the element is rotated through its prescribed arc and back.

During the return rotation, the element 10 is moved in counter-clockwise direction until the projection 101 on the valve part 80 comes into contact with the fixed stop 102. This brings the pawl 86 opposite the recess 99, and continued turning of the means 33 causes the valve part 82 to continue its movement, thereby producing relative movement between the valve parts 82 and 80, and thereby closing the valve. This movement is permitted by the pawl 86 turning into the recess and releasing the lug 95. The valve part 82 continues to move until the projection 105 comes into contact with the shoulder 104 on the valve part 80, which is already held against movement by the coaction of the stops 101, 102. Flow of steam to the element 10 is thus cut off.

It is thus apparent that with this second and more complete embodiment of the invention the return rotation of the blower element is made effective, since the valve remains open until the end of this movement and the steam continues to blow from the nozzles against the boiler tubes during this return rotation; the valve is closed at the end of this movement, after the element has been brought to rest.

In either of the embodiments set forth it is desirable that the element be rotated either continuously or intermittently, as may be desired. For continuous rotation the part 33 may be the usual sprocket wheel engaged by a chain, as indicated in Fig. 15. For intermittent rotation (which for many practical reasons is preferable) the part 33 may be a ratchet wheel moved in one direction or the other by a driving pawl, such, for example, as the mechanism set forth in our Patent No. 1,590,300.

Our invention may be embodied in other

constructions, since it is not limited to the precise embodiment set forth, but may be varied according to local conditions or any changed mode of operation desired, such modifications being within the scope of the appended claims.

What is claimed is:—

1. A soot cleaner comprising a rotary cleaner element, an enclosed valve for controlling admission of steam thereto, said valve movable relatively to the cleaner element and valve-operating means engaging the valve and adapted through the valve to rotate the element.
2. A soot cleaner comprising a rotary cleaner element, an enclosed valve for controlling admission of steam thereto, and valve-operating means adapted to successively operate the valve and rotate the element, said valve and element having abutting stops coacting to transmit rotation from the valve to the element.
3. A soot cleaner comprising a rotary tubular cleaner element, a head through which steam is supplied to the element, a valve in said head, a valve-seat member carried by the element, and valve-operating means adapted to successively operate the valve and rotate the element, with a lock adapted to hold the valve open during the rotation of the element.
4. A soot cleaner comprising a rotary cleaner element, an enclosed valve for controlling admission of steam thereto, and valve-operating means adapted to successively operate the valve and rotate the element, with a lock engaging the valve to hold it open except in the position of rest.
5. A soot cleaner comprising a rotary tubular cleaner element, a head through which steam is supplied to the element, a valve in said head, a valve-seat member carried by the element, and valve-operating means adapted to successivley operate the valve and rotate the element, locking means engaging the valve and seat member adapted to lock the valve in one angular position and release it in other angular positions.
6. A cleaner comprising a rotary tubular cleaner element, a head through which steam is supplied to the element, a valve in said head, valve operating means for opening said valve, said means adapted to rotate the element when the valve is open with locking means for locking the valve in its open position during the rotation of the element, and means in the head controlling said locking means to release the valve and permit it to be closed in the inactive position of the element.
7. In a boiler cleaner, the combination with a blower unit movable about its axis, of an actuating member for said unit including a stem coaxial with said unit and a disk valve directly connected with said stem and mov-

able therewith to control the supply of cleaning fluid to said unit.

In witness whereof, we have hereunto signed our names.

FREDERICK W. LINAKER.
THEODORE M. BRUBACK.
